UNITED STATES PATENT OFFICE.

ANTONIO MARCANTE, OF PATERSON, NEW JERSEY.

LOOM-ALARM.

Specification of Letters Patent. Patented June 27, 1916.

1,188,803.

Application filed January 11, 1915. Serial No. 1,488.

To all whom it may concern:

Be it known that I, ANTONIO MARCANTE, a subject of the King of Italy, and resident of the city of Paterson, in the county of 5 Passaic and State of New Jersey, have invented certain new and useful Improvements in Loom-Alarms, of which the following is a specification.

This invention relates to an indicator mechanism for looms of the class adapted to ring a bell, light lamps or otherwise indicate the presence of trouble in the warp threads before the yarn is broken, and the object of the invention is to provide simple 10 and effective means whereby a member located in the path of travel of the warp threads is arranged to be engaged and moved by a snarl, entanglement, or other irregularity in these threads to cause an indicator to denote the presence of trouble in 15 the warp before the yarn is broken.

With these and other objects in view, the invention consists of certain novel features of construction, as will be more fully described, and particularly pointed out in the appended claims.

In the accompanying drawings: Figure 1— is a diagrammatic view illustrating the general arrangement of a narrow ware loom and my improved indicating apparatus as connected thereto. Fig. 2— is a rear elevation showing a portion of the yarn feed, and a portion of the circuit-closing bars in normal position. Fig. 3— is the same as Fig. 2 showing the ends of the circuit-closing bars as moved into position to close the electric circuit and cause the alarm. Fig. 4— is a detail in perspective illustrating the crossing warp yarns, the tilting circuit-closing 20 wires extending into the path of travel of said yarn and the operating cord which is arranged to be engaged by a snarl or entanglement and moved by the travel of the threads against the circuit-closing wires.

Fig. 5— is a view of one of the circuit-closing wires. Fig. 6— is a view of a modified form of a circuit-closing wire having a double engaging end adapted to be operated by either one or both of two different sections of the moving warp. Fig. 7— is a perspective view of a portion of the circuit-closing bar showing the loop in the end thereof adapted to engage the exposed portion of the wires and close the circuit.

Referring to the drawings 10 designates the ground warp beam and 11 the figure

warp beam, both of which are passed through the loom in the usual way. The figure warp *a* passes over the guide roll 12, weight roll 13, guide roll 14 back around the guide roll 15 whence it joins the ground warp thread *b* and is crossed between the lease rods 16 and 17 on their way through the harnesses 18 and lay 19 to be woven into the fabric at 20 and passed over the breast beam 21 to be subsequently wound upon the take-up roll 22.

My improvement contemplates the provision of means whereby when a knot, snarl, entanglement or other irregularity occurs in the warp threads, to automatically notify the attendant so that the same may be corrected before the yarn has become broken and so save much time in piecing up and also eliminate objectionable knots being made in the warp threads of the fabric. In order to accomplish this in a simple and effective way, I have provided an electric circuit in which is connected an upper contact bar 23 and a lower contact bar 24 both of which are connected by wires 25 through the source of current 26 to a bell 27 or other sound producing indicator or to a lamp 28 or other visible indicators. On this upper bar 23 I have pivotally hung a plurality of circuit closing wires 29, which may be spaced apart or arranged at intervals along this bar throughout the width of the warp threads.

One leg 30 of each of these wires extend up between and into the path of travel of the warp threads while the downwardly projecting 13^g 31 of these wires extends down from the pivot bar 23 adjacent the lower contact bar 24, whereby when a snarl occurs in the moving warp, one or more of the upper ends of these wires is carried forward and the lower end 31 is consequently brought back in contact with the bar 24 thereby closing the circuit between the two and causing the indicating mechanism to be actuated.

In some cases a second set of wires 34 may be hung on the bar 32 to be operated the same as those above described to be tilted on this contact bar and complete the circuit through the lower bar 33. As many series of these wires as desired may be employed along the warp threads, but it is desirable to position one set in front of each lease rod where a snarl would be most likely to cause a thread to be broken.

It is found in practice very desirable to

extend a flexible cord 35 along in back of each set of circuit-closing wires between the open warp threads, whereby when a snarl occurs this flexible cord is first engaged by 5 the same and moved to press against the wires and so close the circuit. By the use of this cord I am enabled to dispense with many of the wires, which would otherwise be necessary in order to cover all of the separate threads in the warp. In this way it 10 will be seen that when a snarl or entanglement occurs in any portion of the warp it is caused to operate some of these tilting wires to close the circuit and sound an 15 alarm or light a lamp or both.

Another feature of my present invention is the provision of circuit-closing bars 36 and 37, and bar 36 being positioned above the weight roll 13, whereby if the figure 20 warp is not let off sufficiently the weight roll will as the warp is fed along engage the bar 36 normally resting on the pin 43 and raise the same so that the loops 37 and 38 will be moved from the insulated portions 25 39 of the circuit wire *c* and close the circuit to sound the alarm or light the lamps. The lower bar 37 is shown as being flexibly supported on springs 44 and provided with a laterally arranged series of pins 40 through which this figure warp *a* is caused 30 to travel and if a snarl occurs in the warp its passage through these pins would be prevented and would cause the bar to move downward so that its loops 41 and 42 would 35 move from the insulated portions 39 to engage the circuit wires *c* and so operate the necessary alarm.

In some cases it is found desirable to construct a circuit-closing wire in the double form as illustrated in Fig. 6 in which I have provided two arms 45 and 46 which may be arranged to engage and be operated by two different sections of the warp yarn, instead

of a single section as is the case of the single wire.

45

I claim:

1. In a loom, an electric circuit, an indicator, a series of circuit-closing members extending into the path of travel of the warp and supported independent of the 50 yarn, means whereby a snarl in the moving warp causes one or more of said members to affect said electric circuit and operate said indicator to denote the presence of trouble before the yarn breaks. 55

2. In a loom, an electric circuit, an indicator, a series of circuit-closing members extending into the path of travel of the warp and supported independent of the 60 yarn, a flexible cord extending along said members whereby a snarl in the moving warp causes said cord to engage one or more of said members and move the same to act upon said electric circuit and operate said indicator to denote the presence of trouble 65 before the yarn breaks.

3. In a loom, an electric circuit, an indicator, an upper contact bar, a lower contact bar, a series of circuit-closing members pivotally supported on said upper bar and 70 having a portion extending into the path of travel of the warp yarn and a portion extending to a point adjacent said lower bar, whereby a snarl in the moving warp is caused to move said members into engagement with said lower bar to affect the electric circuit and operate an indicator to denote the presence of trouble before the 75 yarn breaks.

In testimony whereof I affix my signature in presence of two witnesses.

ANTONIO MARCANTE.
